UNITED STATES PATENT OFFICE

148,445

DESIGN FOR A BROILER

Maurice Samburg, New York, N. Y.

Application October 5, 1946, Serial No. 133,795

Term of patent 3½ years

(Cl. D81—10)

To all whom it may concern:

Be it known that I, Maurice Samburg, a citizen of the United States of America and resident of the city, county, and State of New York, have invented a new, original, and ornamental Design for a Broiler, of which the following is a specification, reference being had to the accompanying drawing, forming a part thereof, in which

Fig. 1 is a perspective view of a broiler embodying my design, with the cover thereof in closed position;

Fig. 2 is a top plan view of the broiler shown in Fig. 1;

Fig. 3 is a perspective view of the broiler, with the cover member thereof in open position; and

Fig. 4 is a front elevation of the broiler with

the cover member reversed and positioned upon the broiler body in such reversed position.

I claim:

The ornamental design for a broiler, as shown.
MAURICE SAMBURG.
